Assistant Examiner — Rebecca Tsehay

CLAIM

The ornamental design for a container for a clothes washing machine, as shown and described.

DESCRIPTION

FIG. 1 is a perspective view of a container for a clothes washing machine;

FIG. 2 is a front view thereof;

FIG. 3 is a rear view thereof;

FIG. 4 is a right side view thereof; and,

FIG. 5 is a left side view thereof.

The broken lines in the drawings depict the boundary of the claim. It is understood that the claim extends to the boundary, but that the boundary forms no part of the claimed design.

1 Claim, 5 Drawing Sheets
